United States Patent Office

Des. 219,403
Patented Dec. 8, 1970

219,403

ORGAN CONSOLE

Thomas E. Kimble, Covington, Ky., assignor to D. H. Baldwin Company, Cincinnati, Ohio, a corporation of Ohio

Filed Dec. 3, 1969, Ser. No. 20,347

Term of patent 14 years

Int. Cl. D17—01

U.S. Cl. D56—2

Fig. 1

FIG. 2

FIG. 1 is a perspective view of an organ console embodying my new design.

FIG. 2 is a side elevation thereof.

The back of the organ console is conventional.

I claim:

The ornamental design for an organ console, substantially as shown and described.
